UNITED STATES PATENT OFFICE.

AUGUSTUS F. SCHMIDT, OF PITTSBURGH, PENNSYLVANIA.

VALVE MECHANISM FOR MOTORS.

1,103,087.

Specification of Letters Patent. Patented July 14, 1914.

Application filed March 13, 1912. Serial No. 683,643.

To all whom it may concern:

Be it known that I, AUGUSTUS F. SCHMIDT, a citizen of the United States, and resident of Pittsburgh, in the county of Allegheny and State of Pennsylvania, have invented 5 a new and useful Improvement in Valve Mechanism for Motors; and I do hereby declare the following to be a full, clear, and exact description thereof.

10 My invention relates to rotary valve mechanism for motors.

The main object of my invention is to provide rotary valve mechanism in which there is a quick opening and closing of the 15 ports while at the same time a comparatively slow motion is imparted to the rotating parts.

Another object of my invention is to provide for the cooling of a rotary valve sleeve 20 on the inside as well as outside.

To these ends my invention comprises the novel features hereinafter set forth and claimed.

In the accompanying drawings Figure 1 25 is a longitudinal section taken through the exhaust valve, the remaining parts of the motor being shown in full lines. Fig. 2 is an end elevation. Fig. 3 is a vertical section through the cylinder and cross-section 30 through valves. Fig. 4 is a view of one of the valves partly broken away. Fig. 5 is a cross-section of one of the valves; Fig. 6 is a detail showing the end bearing for the rotary sleeves; and Fig. 7 shows a modified 35 form of my invention.

In Figs. 1, 2 and 3 of the drawings, I have illustrated my invention in connection with a two-cylinder engine, although it is apparent that any number of cylinders may 40 be employed. The numeral 2 designates the crank-case through which the crank-shaft 3 passes. The piston-rods 4 are connected up to the crank-shaft by the cranks 5 and 6. The upper ends of the piston-rods are connected 45 to the pistons 7 and 8 contained within the cylinders 9 and 10, respectively. The cylinders may all be cast in one piece if desired and this casting is formed with the T-head 11 with the bores 12 at each side of 50 the cylinders. These bores 12 are surrounded by the outside water-jackets 13 and on the inside by the water-jackets 14. The cylinders are provided with the intake ports 15 and the exhaust ports 16.

55 I will first describe the rotary-sleeve mechanism for controlling the supply of gaseous

fluid to the cylinder, and this is the valve mechanism on the left-hand side of the cylinder as shown in Figs. 2 and 3. The mechanism, however, for the exhaust side is identical. Within the bore 12 is the inner rotary valve 17 which consists of a hollow sleeve surrounding the inner concentric core-piece 18 provided with the water jacket 14 connecting with water-jacket 13 by means of 60 cap 19. This hollow valve sleeve 17 is provided with ports 20 arranged 90° apart, the ports leading to one cylinder being staggered with reference to those leading to the other cylinder, as shown in Fig. 4. The 65 outer rotary valve sleeve 21 fits around the inner sleeve 17. Each of the sleeves 17 and 21 have the annular grooves 22 at their inner ends to receive the balls 23 carried by the 70 annular ball-race 24 which is contained within the bore 12, and is held therein by the annular retainer 25 formed as part of the head 19 which is secured to the casting forming the water-jacket, the same as shown 75 at Fig. 4 in connection with the exhaust valve. The core-piece 18 has the ports 27 and 28. The port 27 is the port through which the explosive fluid passes to the cylinder. A pipe 29 is connected up to the core-piece 18 80 said pipe leading from a suitable carburetor. 85

The outer end of the valve sleeve 17 has the threaded seat 30 in which the stud 31 is secured. A work-wheel 32 is keyed to the stud 31 and is held in place by the nut 33. The worm-wheel 32 has formed therein 90 the bevel pinion 34. The bevel pinion 34 meshes with the bevel pinion 35 on the stud-shaft 36 journaled in the casing. This pinion 35 meshes with the internal bevel gear 37 which is secured to the outer sleeve 95 21 by the screws 38.

A worm 39 is carried by the vertical shaft 40 and said worm meshes with the worm-wheel 32. The shaft 40 is provided at its lower end with the bevel pinion 41 which 100 is engaged by the bevel pinion 42 on the crank-shaft 3. The gear connections between the crank-shaft 3 and the inner and outer valve sleeves are so adjusted that the valve sleeves will make a quarter revolution to each revolution of the crank-shaft. Furthermore it is apparent from the above 105 described gearing that the rotary valve sleeves 17 and 21 will be driven in opposite directions. The above mechanism is shown 110 in connection with the exhaust valve Fig. 1, but this construction applies equally well

to the inlet valve. The outer valve sleeve 21 is also provided with ports 43 which correspond to the ports 20 of the inner valve sleeve and said ports are adapted to register at the intake port 15 as indicated in Fig. 3 or upon each quarter of said valve.

It will be unnecessary to describe in detail the valve mechanism controlling the exhaust 16, as it is a duplicate of that described in connection with the valve controlling the intake, and the same reference numerals are employed on like parts, such as 17^a, 18^a, 20^a, etc. The same worm 39 operates both valves, the only point of difference being that the rotary sleeves of the exhaust valves are set so as to open the exhaust port when the intake is closed as indicated in Fig. 3. The exhaust side has the pipe 47 connected up thereto for carrying off the exhaust gases. The valve casings are each provided with the passages 44, 44^a closed by plates 45, 45^a. When it is desired to inspect the valves, these plates may be removed, and by bringing the valve ports into register with each other as indicated at the left of Fig. 3, the operator by removing the plate 45 can look through the ports 27 and 28 into the intake port 15. The exhaust side has the port 48 in the core-piece 18 which is brought into connection with the by-pass 49 leading from the cylinder, so that when the piston passes below the port 48^a the exhaust can begin to take place before the piston begins to ascend. A cooling-jacket 50 is provided for the by-pass 49 in the cylinder casting.

From the above it will be apparent that the valves controlling the intake will make a quarter revolution to each revolution of the crank shaft, and as said valve sleeves rotate in opposite directions, they will be brought into coincidence on the quarter, and this will occur at the intake valve 15 where the gaseous fluid is delivered to the upper end of the cylinder. It is apparent that by having the valves rotating in opposite directions the full opening of the ports will take place quicker than where a single plug valve is employed, and furthermore there also will be a quicker closing of the ports. This also permits the valves to have their ports open the full width for a longer period.

In Fig. 7 I have shown another modified form of my invention in which the cylinder 70 is provided with the valve casings 71 at each side thereof and at one side is the valve mechanism controlling the inlet port 72 and at the other side is the valve mechanism controlling the exhaust 73. In this construction only one rotary sleeve 74 is employed provided with ports 75. The central core-piece 76 is stationary and the gaseous fluid is admitted to the central chamber 77 whence it escapes by the port 78. This port

78 is brought into register with the ports 75 by the rotation of the valve sleeve 74 so that at the time of the admission of the charge to the cylinder it is properly regulated and controlled. On the exhaust side the same construction is employed except that the central core-piece 76^a has the port 79 which communicates with the passage 80 leading to the lower end of the cylinder and which corresponds to the passage 49 of that form of my invention first above described.

While I have described my invention as applied to an explosive engine, I do not limit it to this particular type as it may be applied to steam-engines as well.

What I claim is:

1. The combination of a cylinder, a casing, an inner rotary valve sleeve in said casing, an outer rotary valve sleeve in said casing, a stationary core-piece within said inner sleeve, said stationary core-piece having a passage therein, said sleeves having ports and means for rotating said sleeves in opposite directions whereby the ports in said sleeves are adapted to register with a port in said cylinder and with a port in said core leading to said passage to form communication between said cylinder and said passage.

2. The combination of a cylinder, a casing, a rotary valve sleeve in said casing, a core within said sleeve having a passage therein and a port in communication therewith, means for admitting gas to said passage, means for cooling said core piece, said sleeve having a port adapted to register with a port leading to said cylinder and with the port in said core piece, and means for rotating said sleeve.

3. The combination of a cylinder, a casing, a rotary valve sleeve in said casing having ports adapted to register with a port in said cylinder, a stationary core-piece within said rotary sleeve having an exhaust passage, said exhaust passage communicating with said cylinder when said ports are in register, said core-piece having a port communicating with said passage, and said cylinder having a port at the lower end communicating with said passage.

4. The combination of a cylinder, a piston, piston rod, crank shaft, an inner rotary valve sleeve having ports, a worm wheel connected to said valve sleeve, an outer rotary valve sleeve having ports adapted to coincide with the ports of said first mentioned sleeve, connections between said worm wheel and said outer rotary sleeve, and between said inner rotary sleeve and said wormwheel to rotate said inner sleeve in an opposite direction, a worm engaging said worm wheel, a vertical shaft on which said worm is mounted, and connections between said vertical shaft and crank shaft.

5. The combination of a cylinder, a pis-

ton, a piston rod, crank shaft, an inner rotary valve sleeve having ports, a worm wheel connected to said valve sleeve, bevel gearing on said worm wheel, a bevel pinion 5 engaged by said gear, an outer rotary valve sleeve having ports, a bevel pinion carried thereby engaged by said intermediate bevel pinion, a worm engaging said worm wheel, a vertical shaft supporting said shaft, connections between said crank shaft and said 10 vertical shaft.

6. The combination of a cylinder having a port, an outer valve casing an inner valve casing, rotary valve sleeves between said 15 casings having ports, means for rotating said valve sleeves in opposite directions, said outer casing having a passage coinciding with a passage in said inner casing in line with the port leading into said cylinder and 20 a cover plate on said outer casing closing said passage.

7. The combination of a cylinder, a casing, an inner rotary valve sleeve in said casing, an outer rotary valve sleeve in said 25 casing, a stationary core within said inner casing,

sleeve having a passage therein and a port in communication therewith, means for cooling said core-piece, said sleeves having ports adapted to register with a port leading to said cylinder and with the port in said core-piece, and means for rotating said sleeves in opposite directions. 30

8. The combination of a cylinder, a casing, an inner rotary valve sleeve in said casing, an outer rotary valve sleeve in said casing, a stationary core-piece having a passage therein and a port in communication therewith, said core-piece having a cooling chamber, said sleeves having ports adapted to register with a port leading to said cylinder and with the port in said core-piece, and means for rotating said sleeves in opposite directions. 35

In testimony whereof, I, the said AUGUSTUS F. SCHMIDT, have hereunto set my 40 hand.

AUGUSTUS F. SCHMIDT.
